UNITED STATES PATENT OFFICE.

JOHN L. GIBSON, OF BROOKLYN, NEW YORK.

PISTON-RING CONSTRUCTION.

Application filed December 18, 1924. Serial No. 756,760.

To all whom it may concern:

Be it known that I, JOHN L. GIBSON, a citizen of the United States, and a resident of the city of New York, borough of Brooklyn, in the county of Kings and State of New York, have invented a new and Improved Piston-Ring Construction, of which the following is a full, clear, and exact description.

10 This invention relates to a construction of piston ring. An object of the invention is to provide a simple and efficient construction whereby substantially all types of pistons can be altered to utilize my invention. 15 Another object concerns the provision of means whereby as the piston rings and their grooves become worn they can be readily replaced.

A further object concerns the provision 20 of means whereby the replacement of piston rings is rendered extremely simple as compared to present practice.

A still further object concerns the provision of means whereby the piston rings in 25 their grooves are balanced at all times against the cylinder wall.

The invention is illustrated in the drawings, of which—

Figure 1 is a plan view of the top of a 30 piston with a portion broken away;

Fig. 2 is a side elevation thereof;

Fig. 3 is an inverse plan view;

Fig. 4 is a section taken on the line 4—4 of Fig. 6;

Fig. 5 is a perspective view of a connecting block disposed between portions of the piston rings;

Fig. 6 is a horizontal section taken on the line 6—6 of Fig. 7; and

Fig. 7 is a vertical section taken on the line 7—7 of Fig. 1.

The form of the invention shown in the drawings is a preferred form, although it is understood that modifications in the construction and arrangement of the parts and in the character of the materials used may be adopted without departing from the spirit of the invention as set forth in the appended claims.

50 In general the invention comprises a plate, preferably ringlike, adapted to be disposed against one end of a piston. This plate is provided with a peripheral, dependent flange in the outer surface of which ring-receiving grooves are formed. This flange is adapted to fit into a recess formed by re-

ducing the end of the piston in diameter, against which the plate bears so as to receive the flange. The plate is then bolted against the end of the piston. The ring-receiving 60 grooves are connected by suitable passages to the end of the piston so that steam is admitted into the grooves. Preferably the grooves are separated by a partition or wall, and each groove has in its bottom a central rib or chime through which the above-mentioned passages extend.

Preferably the rings are formed in two half sections to form a complete ring. These rings, in cross section, are preferably 70 U shape with the limbs of the U extending rearwardly and lying on opposite sides of the central rib in the groove. The rings are also pierced or apertured to permit the steam pressure to escape against the outer 75 wall of the ring for purposes of lubrication. The adjacent ends of the rings are separated by blocks which are disposed in the grooves in portions thereof where the central diameter has been cut away, these 80 blocks having portions which interlock with the ends of the ring to make tight joints; and the blocks are provided with means for holding them tightly in co-operative relation with the ring. 85

The preferred form of the invention is shown in the drawings. In accordance with the invention there is a piston 1 the upper end of which is reduced in diameter to provide shoulders 2 and 3. To this end of the piston a ringlike plate 4 is attached, this plate having a dependent, ringlike flange 5, this ringlike flange 5 having ring-receiving grooves 6 and 7 in its outer face. The plate 4 is attached to the end of a 90 piston by means of bolts 8. This plate is provided with steam passages 9 which extend downward into the flange 5 and outward through the ends of the chimes, such as 10 and 11, formed in the bottom of each ring-receiving groove 6 and 7. There are a plurality of these steam passages. The grooves 6 and 7 are separated by a wall or partition 12. Each of the rings such as 13 are U-shape in cross section with the limbs 14 of the U extending rearwardly on opposite sides of the chimes to make a tight joint. Each ring is made in two sections. The adjacent ends of these sections are brought into co-operative relation with the block (see Fig. 5). This block has a base portion 15, a central wall 16 adapted to lie 100

105

110

in alignment with the chimes, and a projecting lug or head 17 adapted to lie in alignment with the ends of the ring. The adjacent ends of the ring are slotted to partially embrace the head 17, as shown in the figures.

The bottom of the flange 5 is provided with a circular groove 18 which is connected by apertures 19 to the bottom 11 to function in a manner similar to the steam passages 9. This groove is connected by a plurality of vertical passages such as 20, shown in Fig. 4, with the other end of the piston.

15 The block which lies between the adjacent ends of the rings has a rearward recess in which a spring 21 is adapted to lie. This spring tends to hold the block outward against the wall of the cylinder and 20 in engagement with the ends of the ring to make a tight joint.

It will thus be seen that by releasing the bolts 8 the top plate and the dependent flange can be equally lifted off the end of the piston so as to remove the rings and 25 their grooves. These can be readily replaced at will in the grooves separated from the piston and then put back into place merely by placing the flange and plate in 30 position and bolting them to the end of the piston.

In this manner any standard piston can

be altered very slightly to adapt it for use in connection with this particular construction of ring-receiving unit.

35

What I claim is:

1. A piston ring construction which comprises in combination a piston having a ring groove, a central chime in said groove, a U shaped ring section lying in said groove 40 with its limbs extending rearwardly to bear against the upper and lower faces of the said chime, the chime being cut away along those portions where the ends of the ring sections lie and a connecting block disposed in the groove, said block having a base to lie against the bottom of the groove, a wall projecting from the base to fill in where the chime has been cut away, and a tongue 45 projecting from the wall, the ends of the ring sections being slotted to receive said tongue.

2. A connecting block for sectional piston rings which comprises a base to lie in the piston groove and bear against the rear face 55 of the ring sections, a wall portion projecting from the base portion and adapted to fill in a gap formed by cutting away a part of a chime in the piston groove, and a tongue portion projecting from the wall 60 portion to lie in slots formed in the ends of the adjacent ring section.

JOHN L. GIBSON.
